UNITED STATES PATENT OFFICE.

DOMINICK PELLETIER, OF FALL RIVER, MASSACHUSETTS.

COMBINED CURTAIN AND SHADE HANGER.

Application filed February 17, 1925. Serial No. 9,798.

To all whom it may concern:

Be it known that I, DOMINICK PELLETIER, a citizen of the United States, residing at Fall River, in the county of Bristol and State of Massachusetts, have invented certain new and useful Improvements in Combined Curtain and Shade Hangers, of which the following is a specification, reference being had to the accompanying drawings.

This invention relates to a combined curtain and shade hanger and it is an object of the invention to provide a device of this general character which can be readily applied in working position without requiring the use of nails, screws or the like.

Another object of the invention is to provide a novel and improved device of this general character which may be readily and conveniently applied into working position or removed and which embodies a structure permitting the same to also be employed to advantage as a clothes hanger.

The invention consists in the details of construction and in the combination and arrangement of the several parts of my improved combined curtain and shade hanger whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan illustrating 40 curtain and shade hangers constructed in accordance with an embodiment of my invention and in applied position with the curtain and drapery rods together with the shade roller being diagrammatically indicated by broken lines;

Figure 2 is a view in front elevation of the structure as illustrated in Figure 1;

Figure 3 is an enlarged fragmentary view 50 partly in section and partly in side elevation illustrating one of my improved hangers as herein set forth;

Figure 4 is a view in perspective of the hanger as illustrated in Figure 3;

Figure 5 is a view in perspective of one 55 of the holding members as herein embodied;

Figure 6 is a view in perspective of the second holding member as herein employed;

Figure 7 is a view in perspective of the clamping member employed when the device is used as a hanger for clothes;

Figure 8 is a view in perspective showing the assembly of the device when employed as a clothes hook or the like.

As herein disclosed, each of my improved devices comprises two relatively movable holding members A and B, each of which being preferably formed of a single strand of wire of requisite gauge.

As particularly illustrated in Figure 5, it is to be noted that the strand is returned upon itself to provide an elongated open loop 1 of requisite dimensions and having its outer portion 2 upwardly disposed or offset. The inner portions of the side members *a* of the loop 1 are formed in the coils 3 and then continued downwardly by the substantially parallel arms 4. The arms 4 are continued by the forwardly disposed and substantially parallel arms 5 continued by the downwardly and inwardly curved members 6 terminating in the upstanding penetrating members or prongs 7.

The member B comprises an intermediate portion or bar 8 which is insertible through the eye members formed by the coils 3 and one end portion of the bar 8 is continued by a perpendicularly related arm 9 terminating in an inwardly disposed penetrating member 10. The opposite end portion of the bar 8 is continued by an elongated loop 11 disposed in a direction substantially opposite to the arm 9 with the returned member 11^a of said loop wrapped around, as at 12, the bar 8 and continued by the arm 9^a substantially in parallelism with the arm 9 and terminating in the inwardly disposed penetrating member 10^a. The loop member 11 is elongated and is adapted, when the device is in applied position, to receive a supporting trunnion for a shade roller.

In applying the device the penetrating member 7 of the member A is engaged with the lower edge of the top facing of a window casing or the like while the penetrating members 10 and 10^a of the member B are engaged with the upper edge of the top facing of a window casing or the like and then the members 6 are pulled down so that the penetrating members can engage the top window facing from below, the inherent re-

siliency of the members A and B and more particularly of the member A causing the assembled members to be solidly held in working position. A trunnion of a shade roller may be engaged within the loop member 11 of each of the applied hangers or if preferred each of the hangers as so assembled may be used as a clothes hook or rack.

To hold an applied shade roller against displacement, I find it of advantage to employ a substantially V-shaped member C which is disposed over the bar 8 of the member B from the rear and between the coils 3, one leg 14 having close contact with the outer face of the top facing with the second leg 15 forwardly disposed. This leg 15 is continued by a returned arm 16 having its free end portion coiled or otherwise secured, as at 17, to the leg 15 at a point adjacent to the junction between the legs 14 and 15. The arm 16 is disposed on outward convergence with respect to the leg 15 and the outer end portions of the leg 15 and the arm 16 are connected by the intermediate 25 and upwardly disposed member 18. The leg and arm 16 are of such length as to extend over the applied shade roller and in close proximity thereto and thereby facilitates maintaining said applied roller against displacement.

It is to be noted that the member C is readily separable from the assembled members A and B so that when desired the member C can be removed to permit the assembled members A and B to be employed as a clothes hanger or rack.

When the member C is applied, the leg 14 is also adapted to provide means to hold in applied position a bracket D for supporting rods for curtains and draperies. As herein disclosed, each of the brackets D comprises an elongated arm 19 provided at its inner end when applied with a depending arm 20 for contact with the top facing while the opposite end portion of the arm 19 is provided with an oppositely disposed arm 21 continued by the outstanding arm 22 disposed substantially in parallelism with the arm 19. The outer end of the arm 22 terminates in a depending arm 23 substantially in parallelism with the arm 20, said arms 20 and 23 serving to effectively hold the arm 19 against rotary movement.

The arm 22 adjacent its opposite ends is provided with the outstanding fingers 24 each of which being adapted to telescopically engage with an end portion of a rod 25 as indicated by broken lines in Figure 1, said rod being adapted to support either curtains or draperies.

In applying a bracket D, the outer end portion of the arm 19 is disposed over the arms 4 and substantially resting on the inner end portions of the arms 5 and the leg 14 of the member C is disposed over the arm

19, the inherent resiliency of said leg 14 serving to effectively clamp the bracket D in working position.

From the foregoing description it is thought to be obvious that a combined curtain and shade hanger constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the class described comprising two members pivotally connected one to another, one of said members comprising a wire turned upon itself to provide an elongated loop, the side members of the loop having their outer end portions continued by downwardly and outwardly disposed arms terminating in upwardly directed penetrating members, said side members of the loop adjacent the arms being provided with eyes; the second member also comprising a wire formed to provide a bar insertable through the eyes of the first member, said bar adjacent its opposite ends being provided with angularly related arms terminating in inwardly disposed penetrating members, the wire at one end portion of the bar being forwardly directed to provide a loop, a retaining member coacting with the bar of the second named member, said retaining member being substantially V-shaped in form disposed over the bar of the first named member from the rear, one leg of said last named member being forwardly directed and returned to provide a loop, and a second leg extending downwardly from the bar and providing clamping means with the outwardly disposed arms of the first member.

2. A device of the class described comprising two members pivotally connected one to the other, one of said members comprising a wire turned upon itself to provide an elongated loop, the side members of the loop having their outer end portions continued by downwardly and outwardly disposed arms terminating in upwardly directed penetrating members, said side members of the loop adjacent the arms being provided with eyes; the second member also comprising a wire formed to provide a bar insertable through the eyes of the first member, said bar adjacent its opposite ends being provided with angularly related arms terminating in inwardly dis-

posed penetrating members, the wire at one end portion of the bar being forwardly directed to provide a loop, a retaining member coacting with the bar of the second named member, said retaining member being substantially V-shaped in form disposed over the bar of the first named member from the rear, one leg of said last named member being forwardly directed, 10 the second leg extending downwardly from the bar, said depending leg providing a clamping means with the outwardly disposed arms of the first member, and a rod bracket adapted to be held in position by 15 said clamping means.

3. A device of the class described comprising two members pivotally connected one to the other, one of said members comprising a wire turned upon itself to provide 20 an elongated loop, the side members of the loop having their outer end portions continued by downwardly and outwardly disposed arms terminating in upwardly directed penetrating members, said side members 25 of the loop adjacent the arms being provided with eyes; the second member also comprising a wire formed to provide a bar

insertible through the eyes of the first member, said bar adjacent its opposite ends being provided with angularly related arms 30 terminating in inwardly disposed penetrating members, the wire at one end portion of the bar being forwardly directed to provide a loop, a retaining member coacting with the bar of the second named member, said retaining member being substantially V-shaped in form disposed over the bar of the first named member from the rear, one leg of said last named member being forwardly directed, a second leg extending downwardly from the bar, and a rod bracket adapted to be held in position by 35 the depending leg of the third member and the outwardly disposed arms of the first member, said rod bracket comprising 40 an elongated portion terminating at one end in a downwardly disposed arm and at the other end in an upwardly directed arm having outwardly projecting elongated loops, said loops providing supporting 45 means.

In testimony whereof I hereunto affix my signature.

DOMINICK PELLETIER.
